UNITED STATES PATENT OFFICE.

CHARLES FORTH, OF CLEVELAND, OHIO.

SEWER-TRAP.

SPECIFICATION forming part of Letters Patent No. 417,636, dated December 17, 1889.

Application filed September 21, 1889. Serial No. 324,694. (No model.)

To all whom it may concern:

Be it known that I, CHARLES FORTH, a citizen of the United States, and a resident of Cleveland, in the county of Cuyahoga and State of Ohio, have invented certain new and useful 5 Improvements in Sewer-Traps; and I do hereby declare the following to be a full, clear, and exact description of the same, such as will enable others skilled in the art to which it appertains 10 to make and use the same.

My invention relates to an improved form of "sewer-trap;" and its objects are, first, to provide a simple, effective, and accessible 15 form of trap which will prevent the escape of gas from the pipe; second, to provide means for opening or closing the entrance for water to the pipe through the trap accessible from within the bowl, and, thirdly, to lessen the initial cost of the trap and expense for 20 adjustment and for repairs.

My invention consists of the combination and arrangement of parts as hereinafter described, shown in the accompanying drawings, and more particularly pointed out in the 25 claims.

In the accompanying drawings, Figure 1 is a section of a sink provided with my improved trap, also in central vertical section. Fig. 2 is a detail of the cap covering the end 30 of pipe.

In the figures, A represents a globular or pear-shaped depression in the basin a, which receives the vertical end of the sewer-pipe B. b is a water-tight joint, formed where the 35 pipe enters the bowl. The end of the pipe B extends to near the upper end of the depression A, and is provided with slots or openings b' at its upper end. A cylindrical cap C is placed over the open end of the pipe B, 40 closing the mouth, but large enough to leave an annular space C' around the pipe. Lugs, as C², integral with the cap fit within the pipe B, of sufficient width to cover the opening b' in the pipe B. A rib C³, in the top of the 45 cap C, serves to turn the cap so that the lugs C² will either cover or uncover the slots b' in the pipe.

In operation, when it is desired to allow the water to flow from the basin into the pipe the 50 rib C³ is turned by hand until the lugs C² cease to cover the slots b', when the water will enter the annular space C' and flow into the pipe;

but on turning the cap so as to recover the slots the water will be retained in the basin. When all the water has been drawn from 55 the basin, enough will be left in the depression A and annular space C' to prevent the escape of gas and make an efficient seal.

The meeting surfaces of the cap and pipe may be re-enforced with rubber or other flexible packing, if desired, so as to be air-tight, and a lug or pin, as b², may be used to stop the cap C. A ring, as D, may be used to turn the cap C, through the sieve E.

The advantages of this device are obvious 65 on account of the extreme simplicity of the working parts and their ready accessibility when the trap becomes fouled and needs cleaning. It will also be evident that when any part wears it can readily be replaced 70 without removing the trap.

I do not claim as my invention the specific form, precise construction, or arrangement of the various parts of my device. Such limitations are not of the spirit of my invention; 75 but

What I claim as new, and desire to secure by Letters Patent, is—

1. In a sewer-trap, a basin having a depressed portion, a vertical pipe extending 80 through the depressed portion of the basin, a cylindrical cap covering the upper opening of said pipe, and forming an annular space around the projecting part of the pipe, in combination with openings in the upper extremity of the pipe and means for covering or uncovering these openings, consisting of lugs depending from the cap and integral with the same, substantially as and for the purpose set forth. 90

2. In a sewer-trap, a basin having a depressed portion, a vertical pipe extending through the depressed portion of the basin, a cylindrical cap covering the upper opening of said pipe and forming an annular space 95 around the projecting part of the pipe, in combination with openings in the upper extremity of the pipe and means for covering or uncovering these openings, consisting of lugs depending from the cap and integral therewith, and a perforated disk covering the opening in the bottom of the basin, with a lug integral with cap and extending vertically through said disk into the basin, all 100

substantially as and for the purpose set forth.

3. In a sewer-trap, the following elements: a basin having a depressed portion, a vertical pipe extending through the depressed portion of the basin, a cylindrical cap covering the upper opening of said pipe and forming an annular space around the projecting part of the pipe, openings in the upper ex-

tremity of the pipe, and means for covering or uncovering these openings, consisting of lugs depending from the cap and integral therewith, and a lug or pin, as b^2 , all as and for the purpose set forth.

CHARLES FORTII.
